UNITED STATES PATENT OFFICE.

EZRA T. WELLS, OF CHICAGO, ILLINOIS.

VEHICLE-SPRING.

1,118,708.

Specification of Letters Patent. Patented Nov. 24, 1914.

Application filed July 19, 1913. Serial No. 779,975.

To all whom it may concern:

Be it known that I, EZRA T. WELLS, a citizen of the United States, residing at Chicago, in the county of Cook and State 5 of Illinois, have invented certain new and useful Improvements in Vehicle-Springs, of which the following is a specification.

My invention relates to improvements in vehicle springs.

One of the salient objects of my invention 10 is to provide a spring for vehicles, and more especially for automobiles, which is adapted to readily adjust itself to suit the variations of load imposed thereon and which will 15 cause as easy riding of the vehicle body when carrying a light load as when it is carrying a heavier load; which is resiliently yielding under ordinary uses and capable of absorbing the shocks due to any sudden or 20 abrupt movement of vehicle wheels, without imparting such shocks to the body.

Other and further objects of my invention will become readily apparent to persons skilled in the art from a consideration of 25 the following description when taken in conjunction with the drawings, wherein—

Figure 1 is a side elevation of the preferred form of spring. Fig. 2 is an end elevation of the same. Fig. 3 shows a side elevation of a slightly modified form. Fig. 4 is an end elevation thereof. Fig. 5 is a side elevation of another, among the many variations that my improved spring may take. Fig. 6 is an end view of the same.

55 In all the views the same reference characters are employed to indicate similar parts.

In the drawing 10 is the upper member and 11 is the lower member of a leaf spring.

12 is the base of the spring, to which the 40 vehicle body is attached and 13 is the base to which the axle of the running gear is attached. The ends, or terminals, 14 and 15, respectively, are so related that the former or inner terminal, in every instance, is 45 curved on a shorter radius and is included within the confines of the curved portion of the outer terminal 15 and these two terminals are connected together by means of shackle bars 16 and 17. The bolts 18 and

50 19 of the shackle bars pass through eyes made in the terminal ends of the longest leaf of the respective springs and the inner terminal member 14, in every instance, is contained between the pair of shackle bars 55 that are connected to the terminals thereof and to the outer terminal of the companion

spring. The shackles, 16 and 17, are cut away, as at 20, to permit free movement of the inner spring without coming in contact with the terminal 14, which the said shackle 60 bars cross, so that any relative vertical movement of the two springs will not cause chafing or noise resulting from frictional engagement of the inner spring with the shackles that connect the terminals of the 65 two springs together.

Fig. 1 shows a complete scroll of two convolutions of the longest leaf of the inner spring, while Fig. 3 shows a portion or incomplete turn of the scroll. Either form 70 comes within the contemplation of my invention and while these two figures show both of the springs at both ends to be of the same relative curvature, in the structure depicted by Fig. 5 each spring has a 75 long curved terminal and a short curved terminal and the same relation of the respective terminals is maintained, with the exception that in this figure the lower spring on one side is within the scroll or curve of 80 the terminal of the upper spring while on the other side the upper spring terminal is within the curved terminal of the lower spring, each spring having a long curve at one end and a short curve at the other. This 85 is a variation without materially affecting the principle of operation, but it is a structure that is well within the definition of the appended claims.

The weight imposed upon the pair of 90 springs tends to curve the terminals of the springs on shorter radii but if the springs are properly proportioned the same relation of curvature will exist under imposed loads, as when the springs are not compressed by the effect of the load.

While I have shown in the drawing, two complete elliptic spring members to compose a pair in each complete spring, it is evident that a spring having parts cut away 100 on either side of the supports, thereby utilizing less than a whole spring above or below would perform the same characteristic functions of a complete elliptic spring, and would fall within the spirit of my invention.

Having described my invention, what I claim with a view and desire to secure by Letters Patent is:—

1. A vehicle spring comprising two co-operating leaf members having their terminal ends curved on different radii, about 110

substantially the same center said ends located one within the other, and a shackle crossing the inner spring and connecting said ends together.

2. A vehicle spring comprising two co-operating leaf members having their terminal ends curved on different radii about substantially the same center, said ends located one within the other, and each end

10 provided with a terminal eye, and a shackle comprising parallel bars, one on each side, and a bolt taking through the ends of said bars and through said eyes for connecting said ends together, said bars crossing the 15 inner spring.

3. A vehicle spring comprising two co-operating leaf members, each gradually curved from their attaching bases to points near their respective ends, one leaf of each 20 spring continuing in a curve on a shorter

radius than the curve of the respective body part; the terminal end of one spring having a shorter curve than the terminal end of the other spring, the end having the shorter curved terminal being within the longer 25 curved terminal and a shackle connecting said ends together and crossing the inner springs.

4. A vehicle spring comprising two co-operating leaf members, having their ends curved to provide scrolls, one within the other, and a shackle crossing the inner spring connecting the free terminals of said scrolls.

In testimony whereof I hereunto set my 35 hand in the presence of two witnesses.

EZRA T. WELLS.
